CLAIM

The ornamental design for an electric vehicle charging station, as shown and described.

DESCRIPTION

FIG. 1 is a front view of an electric vehicle charging station showing the new design;

FIG. 2 is a front, left perspective view of the invention illustrated in FIG. 1;

FIG. 3 is a left view of the invention illustrated in FIG. 1; FIG. 4 is a right view of the invention illustrated in FIG. 1; FIG. 5 is a bottom view of the invention illustrated in FIG. 1;

FIG. 6 is a top view of the invention illustrated in FIG. 1; and,

FIG. 7 is a rear view of the invention illustrated in FIG. 1. The broken lines in the drawings depict portions of the electric vehicle charging station that form no part of the claimed design.

1 Claim, 7 Drawing Sheets
